COURT AND TRAFFIC MARKER

George L. Lane, Ardmore, Pa.

Application August 18, 1932. Serial No. 629,316

4 Claims. (Cl. 91—39)

The object of the invention is to provide improvements in markers broadly, but more especially in devices of this character which are used to mark the outlines and playing areas of tennis courts, baseball diamonds, football gridirons, and the like, and which can also be used for marking the traffic lines upon road surfaces.

A further object is to provide in such a device the combination of what will be termed a rotary marking element and a trailing or frictional marker element, with independent means to control the flow of the usual paint or marking fluid to them, which means however are usually actuated in unison, together with other details adapted to facilitate the general operation of the device, such as providing common means to regulate the flow of the marking fluid to the brush to depress or elevate the brush in substantial unison but as hereinafter described.

20 In order to better understand the invention, it should be stated that while it is known to be old to use a rotary marking element alone, and also old to use a trailing or frictional marking element alone, so far as is known it is novel to operatively combine the two elements in a single marker, so as to receive the marking fluid simultaneously from a single reservoir.

Among the advantages of this combination, hereinafter more fully brought out, is that when 30 operated simultaneously, the surface of the rotary element receives the fluid and presses it well against and into the surface of the ground, whether the latter is covered with grass or not, whereupon the under surface of the other element brushes or lightly drags over the newly wetted surface and simultaneously sheds from its upper surface a constant flow of the marking fluid, while the first application by the rotary element is still wet, thus insuring a more dense 40 and lasting double application of the fluid, than is possible if either of the two elements were to pass twice over the playing or road surface in order to apply a double coat of the fluid thereto, besides the fact that it is very difficult if not impossible in practice to apply a second coat over and in exact alignment with or superposed upon a first coat previously deposited by the same or a different device.

Still other objects are, to provide a novel means 50 for removably attaching the brush or similar element to the device; to provide means for positively maintaining alignment of the two marker elements; to provide a combination strainer and splash-preventing baffle for the filling opening of the reservoir; and to provide additional features

hereinafter brought out in detail in the following description, when read in conjunction with the accompanying drawings, in which Fig. 1 is a vertical front to rear section of a marker comprising one embodiment of the invention; Fig. 2 is a section on the line 2—2 of Fig. 1; Fig. 3 is a front elevation of the device; Fig. 4 is an enlarged plan view of the trailing brush element; Fig. 5 is a section on the line 5—5 of Fig. 4; and Fig. 6 is a fragmentary detail of the same in depressed or 60 operative position.

Referring to the drawings, one embodiment of the invention comprises a tank formed of a cylindrical major portion 1, which in turn comprises the diagonally upward and rearward continuation 70 of the similarly shaped sides 2 of a lower casting, which is closed by a bottom wall 3. This tank is positioned between a pair of substantially parallel longitudinally extending frame members 4, which adjacent to the upper limit of said cylindrical 75 portion diverge at 5 and have secured to their angularly free end portions 6 manually engageable handles 7 of any suitable size, shape, and convenient arrangement. From substantially the central portions of said frame members 4 there 80 extend downwardly and rearwardly a pair of additional frame members 8, which are preferably substantially parallel in arrangement and support between their lower free end portions an axle 9, upon the opposite end portions of which are 85 mounted wheels 10. In order to make this frame structure rigid, a further pair of spaced substantially parallel and practically horizontally extending members 11 connect the lower portions of the first-named frame members 4 with the second set 90 of frame members 8, preferably above the level of the wheels 10, thereby providing a substantially rigid triangular unit frame structure, which may be secured to said tank or reservoir in any suitable manner.

To the outer surface of the bottom wall 3 of said tank is secured any suitable shape of bifurcated bracket 12, between the spaced outer free end portions of which is rotatably positioned a marker wheel 13, operatively supported upon a pin 100 or shaft 14. Above the upper central portion of said marker wheel is positioned a valve 15, which leads from the interior of said tank through an aperture 16 and is adapted to discharge a relatively slender stream of marking fluid upon the 105 outer surface of said last-named wheel, under the control of a valve lever 17, from which a rod 18 extends to a point adjacent to one of the handles 7. Each of these handles is provided with a depending apertured lug 19 which pivotally sup-

ports a suitable trigger or bell crank lever 20, one arm of which is in one instance connected to the rod 18 and in the other instance, adjacent to the other of said handles, is connected to a rod 21, which leads toward and is pivotally attached to the operating lever 22 of a second valve 23, which also connects with the interior of said tank through a suitable aperture 24, and is adapted to discharge a relatively slender stream of marking fluid downwardly and rearwardly, as hereinafter described.

Each of the arms of the bell crank levers 20, to which the rods 18 and 21 are connected, is also connected by means of a spring 25 to an adjacent portion of the side frame members 4, so that the valves 15 and 23 are normally closed, and are opened by manual engagement of one or more fingers of each hand with the depending arms of the respective bell crank levers 20, thereby permitting the opening of the valves simultaneously or independently of each other and to varying degrees when and as may be desired.

The lower portion of the tank or reservoir is provided with a pair of spaced depending lugs 26, between which is pivotally mounted a discharge trough 27 shown specifically in Figs. 4 and 5. This trough primarily comprises a bottom wall 28, from which rise a rear wall 29 and laterally opposite side walls 30, while the rearmost edge portion of said bottom wall is unobstructed, so as to freely discharge therefrom marking fluid, which falls upon said wall from the valve 22. To the under side of said bottom wall there is secured in any suitable manner, as by means of a screw 31, the handle portion 32 of a brush 33, or in fact any other suitable device adapted to receive such marking fluid upon its upper surface and discharge such fluid from its rearmost trailing edge portion, after its lower surface has trailed upon the surface of the ground, when in normal operation, as shown in Fig. 6.

It will be noted that the upper surface of the bottom wall 28 of the discharge trough 27 is preferably provided with a plurality of ribs or corrugations 34, the purpose of which is to control and equalize the flow of marking fluid towards and longitudinally across the upper surface of the exposed portion of the brush 33, so that the line, ribbon, or band of paint or other marking fluid left by the improved marker to the rear of said brush will be as nearly uniform as possible in thickness and free from lines, which would be caused by the brush were the latter to pass frictionally over the fluid after having been deposited upon the ground surface, instead of the fluid flowing over and freely away from said brush.

It is to be understood, furthermore, that in referring to a brush, any suitable element adaptable for this purpose is anticipated, such for instance as a relatively flexible spatula, which might be formed of thin flexible metal, such as steel, or might be formed of rubber or the like. It will also be noted that the valve lever 22 is connected by means of a chain 34 or the like, to a suitable portion of said discharge trough, as for instance to one of the side walls 30 thereof, and that in operating the rod 21, the brush 33 is lowered into operative position in frictional contact with the ground surface before there has been sufficient movement of said valve lever to permit the flow of marking fluid through said valve. Thus, the flow of such fluid is positively shut off by a reverse movement of the rod 21, before said brush is raised freely above the ground surface, it being also possible when desired to

first shut off the flow of fluid through the valve 23 and continue to permit the brush to contact with the ground, before raising the brush freely therefrom, in order that the fluid last discharged and dripping from said valve shall have a full opportunity to reach and pass from the free edge portion of the brush, before the latter is raised.

In addition to the structure thus described, there may be positioned in the upper free end portion of said tank a cylindrical closure 35, the side walls of which preferably terminate in a diagonal plane defined by inturned flanges 36, across and between which extends a metal gauze 37, adapted to strain and remove solid particles from the marking fluid as it is poured into the tank thru this cylindrical closure. Also, in order to prevent any splash of the fluid, as it encounters the lower portion of the side walls of the tank or fluid previously placed therein, a preferably flexible baffle plate 38 extends diagonally into said tank below the gauze 37, and is secured in any suitable manner at one peripheral portion 39, substantially as shown in Fig. 1.

In the operation of this marker, it is of course obvious that either of the valves 15 and 23 may be opened independently of the other, as well as being adapted to open concurrently for the simultaneous deposition of marking fluid. However, it is to be understood that the latter method of operation is by no means a mere duplication, or doubling-up, of the former for several reasons. In the first place, by operatively associating the two types of fluid-depositing mechanism in the same apparatus, positive alignment of the two applications is assured, so that the second is certain of being placed directly upon and in registry with the first.

In the second place, by opening the forward valve 15 and permitting the brush 33 to trail lightly upon the band of fluid deposited by the wheel 13, without opening the rearward valve 23, a certain smoothing of the band of but one coat is possible. Then again, by opening the rear valve in addition to the front valve it is possible to apply a second coat of the marking fluid before the first coat dries. Also, by so doing it is obvious that, as for instance upon ground which has not been previously marked, the first coat will serve as a so-called "filler coat", shortly after which the second coat will be applied without any semblance of scraping, wiping or brushing operation as such. This is by reason of the fact that the brush wipes and smoothes over only the first coat, immediately prior to its applying the second coat, by merely flowing the latter evenly upon the former. Still again, it is possible, if desired, to use the wheel 13, with the forward valve 15 closed, as a roller for pressing, firming-down, or rolling the turf, in preparation for the coat of marking fluid to be flowed upon the same by the brush. However, the advantages of this composite structure and its operation are probably best seen when marking a grass surface, in which case the pressure of the fluid-wetted wheel 13 first upon the grass both wets the latter down to the surface of the ground, and flexes the blades of grass forwardly so as to lessen their inherent stiffness, and thus offer less opposition to the light passage of the brush thereover, as the latter deposits upon the wetted grass-and-ground surface the flowing second coat, thereby leaving a resulting strip, ribbon, or band, of infinitely better and more uniform appearance and paint formation than has been proved to be otherwise possible.
